UNITED STATES PATENT OFFICE

RALEIGH J. HIMMELRIGHT, OF NEW ROCHELLE, NEW YORK, ASSIGNEE TO GENERAL
REFRACTORIES COMPANY, OF PHILADELPHIA, PENNSYLVANIA, A CORPORATION
OF PENNSYLVANIA

REFRACTORY ARCH BRICK

Application filed March 21, 1928. Serial No. 263,871.

My invention relates to locomotive fire boxes and particularly to a novel interlocking brick arrangement for use in connection therewith.

5 In certain types of fire boxes a refractory inclined wall or baffle is employed, the bricks composing the wall resting on inclined arch tubes arranged in proper position within the fire box. In those fire boxes in which the 10 space between the tubes is relatively great, it is customary to fill the space with pairs of inclined bricks, the inner abutting ends of which are interlocked.

In order to simplify manufacture and installation of these bricks it is desirable that the interlock arrangement be such that "rights" and "lefts" are not required; in other words, so that one pattern may be used for both bricks of a pair. This is accomplished 15 in previously suggested constructions by the use of half tongue and half groove interlocking devices and in other ways. In each of the 20 forms known to me, the projections are relatively fragile and likely to be broken in handling and installation.

In the design here disclosed I provide the abutting faces of the brick with relatively large, heavy and substantial projections and so arrange the respective projections and recesses that the functions and advantages of 25 the preceding forms are retained.

The invention will be more readily understood by reference to the accompanying drawings, in which—

30 Fig. 1 is a transverse sectional view through a fire box arranged in accordance with my invention;

Fig. 2 is an enlarged sectional view with 35 a pair of arch bricks in interlocking relation, and

Fig. 3 is a perspective view of one of the bricks.

In the drawings the walls of the fire box are indicated generally by the numeral 10. 40 Within the fire box are two inclined arch tubes 11 that act as a support for the interlocking bricks of my invention. These bricks which are of duplicate form are numbered 12, 13 and have at one end a socket 14 fitting the arch tubes, the body of the brick being

progressively thickened from the lower to the upper end.

On the face of the end opposite to the end containing the socket 14 I provide a plurality of projections and recesses, the projections being indicated by the numerals 15 and 16 and the recesses by numerals 17 and 18. The projections and recesses each occupy substantially one-fourth of the area of the face of the brick and respectively occupy angularly 55 diametrically opposite positions on said face. The projections and recesses are of rectangular or right angular form, both in elevation and in cross section, and the projections are of substantially uniform thickness throughout, thus providing a maximum of material 60 therein. Breakage is thus avoided due to the absence of small and fragile projections.

It will be obvious that the bricks may be installed without skill on the part of the 65 workman as each is a counterpart of the other. It is obvious also that some modification may be made in the construction shown without departure from the spirit of my invention.

I claim:

1. In a locomotive arch the comb of a pair of bricks adapted to be supported in inclined relation with their abutting ends interlocked, the ends being counterparts the face of each end consisting of two projections and two 70 recesses all of rectangular cross section each projection and each recess occupying substantially one-fourth of the area of the face.

2. In a locomotive arch the comb of a pair of bricks adapted to be supported in inclined 75 relation with their abutting ends interlocked, the ends being counterparts the face of each end consisting of two projections and two recesses all of square outline as viewed from the face of the projection and of right angular transverse section, each projection and each recess occupying one-fourth of the area 80 of the face.

3. A brick for locomotive arches comprising a body of refractory material with the 85 face of one end in a plane at an acute angle to the longitudinal axis of the brick, the face being provided with two projections each covering substantially one-fourth of the area of the face, the material comprising the pro- 90

jections being of substantially uniform thickness throughout.

4. A brick for locomotive arches comprising a body of refractory material with the face of one end in a plane at an acute angle to the longitudinal axis of the brick, the face being provided with two projections each covering substantially one-fourth of the area of the face, the material comprising the projections being of substantially uniform thickness throughout, the projections being flanked by recesses covering the remainder of the area of the face.

5. A brick for locomotive arches comprising a body of refractory material with the face of one end in a plane at an acute angle to the longitudinal axis of the brick, the face being provided with two projections each covering substantially one-fourth of the area of the face, the material comprising the projections being of substantially uniform thickness throughout, the body of the brick being of gradually increased thickness from its lower to upper end.

23 In testimony whereof I have affixed my signature.

RALEIGH J. HIMMELRIGHT.
